UNITED STATES PATENT OFFICE.

HENRY V. DEMPSTER, OF MINNEAPOLIS, MINNESOTA.

TOY FLYING MACHINE.

Application filed June 8, 1923. Serial No. 644,362.

To all whom it may concern:

Be it known that I, HENRY V. DEMPSTER, a citizen of the United States, residing at Minneapolis, in the county of Hennepin and 5 State of Minnesota, have invented certain new and useful Improvements in Toy Flying Machines; and I do hereby declare the following to be a full, clear, and exact description of the invention, such as will 10 enable others skilled in the art to which it appertains to make and use the same.

This invention relates to a toy and particularly to a toy in the form of an aeroplane. Aeroplane toys continue to be exceedingly 15 interesting and entertaining to children, especially toys in which the aeroplane moves through the air.

It is an object of this invention to provide a toy simulating a small aeroplane having 20 means thereon for causing the same to circle in the air.

It is a further object of the invention to provide such a toy comprising an aeroplane having a fuselage and a transverse plane 25 thereon, said plane having a flexible string extending centrally therefrom, the outer end of which string is attached to the end of an elongated rod forming an operating handle.

It is still another object of the invention 30 to provide such a toy comprising an aeroplane having a hollow fuselage substantially rectangular or square in cross section, a removable plane extending transversely thereof, a pin loosely mounted beneath the plane 35 to which one end of a string is connected, the other end of said string being secured to the end of an elongated handle.

These and other objects and advantages of the invention will be fully set forth in the 40 following description made in connection with the accompanying drawings in which like reference characters refer to the same parts throughout the different views, and in which

45 Fig. 1 is a plan view of the device;

Fig. 2 is a vertical section taken on the line 2—2 of Fig. 1, as indicated by the arrows; and

50 Fig. 3 is a view in end elevation of the device as seen from the right of Fig. 1.

Referring to the drawings, a toy is illustrated comprising a device simulating an aeroplane structure having a fuselage member 1. The member 1 is hollow and preferably made from a single rectangular blank 55 of light sheet material, such as cardboard,

having a tab extending from one end thereof. The said blank is folded to form an open ended box substantially rectangular or square in cross section. The corners of said box are slotted and the sides of the box at said slits fold inwardly and are fastened together by glue, or other suitable means, thus forming inwardly projecting ribs 2, as shown in Fig. 3. The ends of the member 1 are thus given a tapered shape and the same conveniently reinforced. The tab at the end of the blank is then folded substantially at right angles to the sides of said box and glued, or otherwise fastened in position to form a closed end 3 for the fuselage. The top side of the member 1 is transversely slotted at spaced points somewhat toward the front end thereof, to provide oppositely disposed lips 4. The rear end of the member 1 is open and the sides thereof are transversely slotted to receive a horizontal tail rudder 5 which is glued or otherwise suitably secured to the member 1 and also has secured thereto a vertical tail rudder 6 disposed in a slit in the top side of the member 1 and having its lower edge bent substantially at a right angle and glued or otherwise secured to the member 5. A small headed pin or tack 7 is secured axially in the front end 3 of the member 1 and has journaled thereon a helical blade 8 having oppositely extended arms. A wing or plane member 9 of flat sheet material is provided and is removably held in position on the member 1 by having its sides extending under the lips 4. The member 9 will be bent somewhat along the longitudinal axis so as to dispose the sides beneath the lips 4 and when said member is in position. It will preferably be held 95 in slightly curved form. A pin 10 is loosely mounted beneath the plane 9 and the latter has a small aperture extending centrally therethrough, through which extends a cord or string 11, one end of which is secured to the pin 10. The other end of the string 11 is secured adjacent one end of an elongated rod 12 forming a handle member.

In operation, the rod 12 is held adjacent its free end and the other end swung about the head or in the form of a figure 8 in front of the operator. The aeroplane thus moves through the air in flying position and the pressure of the air against the blade 8 causes the same rapidly to revolve and the aeroplane thus appears to fly through the air. The string 11 is swivelly connected to

the plane 9 by the loose pin 10 so that there is no twisting of the string as the toy is operated. The plane 9 can readily be removed by bending the same and withdrawing it from beneath the lips 4 when the toy is packed, or if it is necessary to examine the connection of the string. The toy is constructed so as to be balanced about the axis from which the string 11 extends so that it will maintain a proper balance or flying position. The string, of course, should be of sufficient length to allow the aeroplane to have considerable scope of travel and with a little practice the aeroplane can be made to do many flying stunts. The propeller continually revolves and produces a buzzing sound, thus simulating, in a remarkable degree, an actual flying machine.

From the above description it is seen that applicant has provided an extremely simple and efficient toy and one which will greatly interest and amuse children. The device is very easily and quite inexpensively made and can be marketed at a very reasonable figure. The same has been amply demonstrated in actual practice and found to operate very successfully.

It will, of course, be understood that various changes may be made in the form, details, arrangement and proportions of the parts without departing from the scope of applicant's invention, which, generally stated, consists in a device capable of carrying out the objects above enumerated and such as shown and described and set forth in the appended claims.

What is claimed is:

1. A toy device comprising a hollow plane having a hollow closed fuselage of sheet material, a plane adjacent the forward end of said fuselage having its front and rear edges detachably inserted in the top of said fuselage, a pin secured in and projecting forwardly from the front of said fuselage, a freely revoluble helical blade journaled on said pin, a string passing through said plane in line with the longitudinal axis of said fuselage and retaining means on said string between said plane and fuselage, and a comparatively long rod to one end of which said string is attached.

2. A toy device comprising an aeroplane having a hollow fuselage of sheet material, a plane detachably connected to the top of said fuselage, horizontal and vertical tail rudders secured to the rear of the fuselage, a freely revoluble blade mounted at the front of said fuselage, a string passing through the top of said plane at the trans-

verse center and substantially at the longitudinal center thereof, retaining means for said string disposed loosely beneath said plane to which one end of the string is secured, and an elongated handle rod to one end of which the other end of said string is secured.

3. A toy device comprising an aeroplane having a hollow substantially closed fuselage made of sheet material and being substantially square in cross section, the top of said fuselage being oppositely slotted to form spaced oppositely directed lips, a plane of sheet material having its sides disposed under said lips and held in place thereby, a cord extending centrally through the top of said plane, means secured to said cord beneath said plane for holding the cord in position, said fuselage being slit at its corners adjacent its front and rear ends and the edges of said slits being inturned and secured together to give the fuselage a tapered shape and forming reinforcing means therefor.

4. A toy device comprising an aeroplane having an elongated hollow fuselage substantially square in cross section and made from a blank of folded light sheet material, said folded blank being slit at its corners adjacent each end of the fuselage and the slit edges folded inwardly substantially at an angle of 45 degrees and secured together to form reinforced tapered ends on the fuselage, the top of said fuselage being provided with oppositely directed slits, a plane having its longitudinal edges inserted in said slits and having a central aperture therethrough, a short rod disposed between the top of the fuselage and said plane, and a string attached centrally to said rod and passing out through the aperture in said plane and forming a manipulating member for said toy.

5. A toy device comprising an aeroplane having a hollow closed fuselage of sheet material, a plane adjacent the forward end of said fuselage having its front and rear edges detachably inserted in the top of said fuselage, a pin secured in and projecting forwardly from the front of said fuselage, a freely revoluble helical blade journaled on said pin, means engaging the underside of the top of said fuselage for securing a string, and a string attached to said means and extending upwardly therefrom substantially centrally of said plane and a comparatively long rod to one end of which said string is attached.

In testimony whereof I affix my signature.
HENRY V. DEMPSTER.
